[57] CLAIM

The ornamental design for combined drop light and extension cord attachment therefor, as shown and described.

DESCRIPTION

FIG. 1 is a bottom, rear perspective view of the combined drop light and extension cord attachment therefor showing my new design;

FIG. 2 is a top, front perspective view thereof;

FIG. 3 is a front elevational view thereof;

FIG. 4 is a side elevational view thereof as seen from the side opposite that shown in FIGS. 1 and 2; and

FIG. 5 is a top plan view thereof.
